EX DESIGN.
OR D 20,981 —
J. PEGEL.
TABLE COVER.

No. 20,981.

Patented Aug. 11, 1891

UNITED STATES PATENT OFFICE.

JULIUS PEGEL, OF PHILADELPHIA, PENNSYLVANIA, ASSIGNOR TO JOHN BROMLEY & SONS.

DESIGN FOR A TABLE-COVER.

SPECIFICATION forming part of Design No 20,981, dated August 11, 1891.

Application filed January 30, 1891. Serial No. 379,705. Term of patent $3\frac{1}{2}$ years.

To all whom it may concern:

Be it known that I, JULIUS PEGEL, a subject of the Emperor of Germany, residing at Philadelphia, in the county of Philadelphia and State of Pennsylvania, have invented a certain new and original Design for a Table-Cover, of which the following is a specification, reference being had therein to the accompanying drawing.

My invention relates to the surface ornamentation of a table-cover; and it consists of the design illustrated in the accompanying photographic drawing, its leading features being the border A and the floral center-piece B.

I claim—

The design for a table-cover, substantially as shown and set forth.

In testimony whereof I affix my signature in presence of two witnesses.

JULIUS PEGEL.

Witnesses:

EDWARD BROMLEY,
ADOLPH PETZOLD.
